UNITED STATES PATENT OFFICE.

FRANK TEMPLEMAN, OF CHICAGO, ILLINOIS.

FOUNTAIN-BRUSH.

1,228,847.

Specification of Letters Patent. Patented June 5, 1917.

Application filed December 31, 1914. Serial No. 879,886.

To all whom it may concern:

Be it known that I, FRANK TEMPLEMAN, a citizen of the United States of America, and a resident of Chicago, county of Cook, 5 and State of Illinois, have invented certain new and useful Improvements in Fountain-Brushes, of which the following is a specification.

The main objects of this invention are to 10 provide an improved fountain brush; to provide a brush of this nature with means for directing fluid streams from the sides of the brush toward its center, to there meet in the axial center line of the brush and produce 15 a fountain causing the water to spread outwardly from the center of the brush to the contact ends of the bristles; to provide a fountain brush with improved clamping means for securing the brush to the holder; 20 and to provide a fountain brush with an improved arrangement of jet orifices whereby the brush is kept in thoroughly cleaned condition while in operation.

An illustrative embodiment of this invention is shown in the accompanying drawings, 25 in which—

Figure 1 is a perspective view of a fountain brush constructed according to this invention.

Fig. 2 is a vertical longitudinal section 30 of the brush.

Fig. 3 is a plan view of the brush stock and part of the brush holder.

Fig. 4 is a perspective view of a sponge 35 and its support which may be secured in the brush holder as a substitute for the brush.

This invention provides a construction of fountain brush which is particularly suitable for cleaning automobile bodies. It is 40 usually necessary to employ a sponge for this work since brushes as ordinarily constructed, cause the grit and dirt which is being removed to scratch the finish of the automobile. Fountain brushes have been

45 constructed to direct a stream of water slightly in advance of the brush and some have been arranged to direct streams of water into the brush and also from the center out, but they have all been arranged in 50 such manner that the ultimate result is impracticable for the class of work which is the aim of the present brush to accomplish. Prior devices frequently required a special construction of brush since the water was 55 directed through its back, and others were not thoroughly self-cleaning since the jets

of water were directed at the sides of a brush having the bristle tufts so arranged as to prevent the water from reaching the center of the brush and keeping it thoroughly saturated with a flow of liquid from the center outwardly. 60

In the present construction, the tufts of bristles are arranged in rows radiating from the center of the brush, thus providing a 65 plurality of open spaces through which the streams of water may be directed so as to produce a fountain at the center of the brush. In this manner, the water flows outwardly toward the operating or contact ends 70 of the bristles, permitting the brush to be used with equal success when in inverted position. In the fountain brushes of this class which may now be obtained on the market, the water fails to thoroughly moisten the entire operating surface of the brush when used in inverted position, most of the water flowing over the outer edge of the brush stock, and being entirely useless, with the result that the grit, etc., scratches the 75 surface being cleaned. For this reason no brushes have been provided which are successful for cleaning automobile bodies, and this work is generally accomplished by means of a sponge. 80

The present invention provides a very substantial brush with a cast holder provided with a cored out water conduit surrounding its periphery, thus permitting the brush to withstand severe use without the water conduit becoming bent, and the present invention also provides a brush which, because of the peculiar manner of flow of water through the brush, may be successfully employed for extremely heavy work without 90 injury to the surface operated upon. 95

Referring to the drawings, the brush support 1 consists of a casting forming a back 2 having a central opening or slot 3 for receiving a cam or clamping device 4 mounted 100 on the stock 5 of the brush. The cam 4 is rotatably mounted and is adapted to readily slip through the slot 3 when turned longitudinally therewith. It may then be turned transversely to the slot, the shoulders thereof of riding upon and engaging the back 2, as shown in Fig. 2. The casting 1 at one end has extending from one end a threaded socket 6 for receiving a brush handle 7 comprising a plurality of pipe sections coupled 105 together to form an extensible handle to which a hose coupling may be secured. The 110

casting 1 has an enlarged outer rim 8 which is cored out to provide a circular water conduit and is provided with a plurality of jet orifices 9, the orifices at opposite sides of the 5 conduit being arranged to direct streams of water radially toward the center of the brush and to meet in pairs along a line passing through the center of the brush transversely to the plane of the back thereof. A 10 few of the jet orifices are arranged to direct water against the tufts of bristles at the outer edge 10 of the body of bristles in order that the matter to be removed from the surface being cleaned is moistened in advance 15 of the brush. By the arrangement of jet orifices meeting on a center line passing through the brush, a fountain is there created which causes the water to flow outwardly to the operating ends of the bristles, 20 even when the brush is used in an inverted position on the under side of a car body.

For the purpose of causing the operating surface of the brush to conform more closely to the form of the fountain produced in the 25 center of the brush, the brush stock 5 is made of decidedly convex curvature. Also for the purpose of not obstructing the flow of water toward the center of the brush, the tufts of bristles 11 are arranged in rows between the jet orifices in the holder, which rows radiate from the center of the brush 30 outwardly, as shown in Fig. 3.

A special cast back 12 is provided for supporting a sponge 13 which may be stitched 35 to the back with chamois 14, as shown in Fig. 4. The sponge may therefore be readily substituted for the brush when it is desired to use the device in light work where a sponge may be preferred. In manufacturing 40 the brush holder, the core for the conduit is supported through the member 6 and apertures 15. These apertures are finally closed by screws, as shown in Fig. 1, and provide means by which the conduit may be 45 flushed out if necessary.

A rubber buffer 16 is provided surrounding the rim of holder 1 to prevent injury to surfaces being cleaned by contact with said holder.

50 In the operation of the device, the water

which enters the brush holder from the handle 7 flows in two streams to the right and left around the cored out conduit at the periphery of the holder. The jet orifices being suitably proportioned with this conduit 55 cause the water to flow in a plurality of streams of substantially equal strength between the rows of bristles and meet in pairs of streams in the axial line of the brush center, producing a fountain which causes the 60 water to flow outwardly to the operating surface of the brush, regardless of the position in which the brush is held during its motion over the surface being cleaned.

It may be seen from the foregoing that 65 the present invention provides a highly efficient fountain brush particularly useful where the brush is employed in rather heavy work.

Although but one specific embodiment of 70 this invention has been herein shown and described, it will be understood that some of the details of the construction shown may be altered or omitted without departing from the spirit of this invention as defined by the 75 following claims.

I claim:

1. A fountain brush, comprising a brush and brush holder, said holder being provided with a conduit encircling the brush 80 and having opposed jet orifices arranged to direct streams at different angles so as to meet at points in different planes more or less removed from the brush holder.

2. A fountain brush comprising a brush and brush holder, said brush being provided with radial rows of bristle tufts, and said holder being provided with a conduit encircling the brush and having opposed jet orifices arranged to direct streams between 90 the rows of tufts at different angles so as to meet at points in different planes more or less removed from the brush holder.

Signed at Chicago this 26th day of Dec., 1914.

FRANK TEMPLEMAN.
